UNITED STATES PATENT OFFICE.

GEZA D. BERKO, OF NEW YORK, N. Y.

DESIGN FOR A WATCH-FOB.

48,342.

Specification for Design. Patented Dec. 28, 1915.

Application filed May 11, 1915. Serial No. 27,464. Term of patent 3½ years.

To all whom it may concern:

Be it known that I, GEZA D. BERKO, a citizen of the United States, and a resident of the borough of Manhattan, city and State of New York, have invented a new, original, and ornamental Design for a Watch-Fob, of which the following is a specification.

My design is represented in the accompanying drawing, in which;

Figure 1 is a front plan view of the watch fob illustrating my new invention. Fig. 2 is a rear plan view of the watch fob illustrating my new invention.

As shown, the design consists of an ornamental shape having on one side a replica of the Hungarian coat of arms, with a

ribbon design on the border containing the lettering as illustrated and on the other side the numerals 1914 made in a raised effect. The general effect of the figures is raised and they may have any coloring desired.

I claim:

The ornamental design for a watch fob substantially as shown and described.

In testimony that I claim the foregoing as my own, I have affixed hereto my signature in the presence of two witnesses.

GEZA D. BERKO.

Witnesses:

GEZA KENDE,
E. W. ALEXANDER.
